UNITED STATES PATENT OFFICE

2,028,660

PENCIL SHARPENER

Elias Ernest Grossman, Chicago, Ill.

Application November 6, 1934, Serial No. 751,774

1 Claim. (Cl. 120—87)

This invention relates to certain new and useful improvements in pencil sharpeners.

The primary object of the invention is to provide a pencil sharpener of the type that may be permanently attached to a pencil and when rotated on the pencil produces a tapered point on the latter with the lead or carbon of the pencil projecting through the sharpener.

A further object of the invention is to provide a sharpener of the foregoing character that has threaded engagement with the pencil with said threaded engagement providing an interlocking connection between the pencil and sharpener to prevent loss of the latter.

It is a further object of the invention to provide a pencil sharpener having threaded engagement with a pencil with a thread cutting device carried by the sharpener for cutting a thread into the pencil body in advance of the threaded portion of the sharpener to facilitate rotation of the sharpener on the pencil during operation thereof.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a side elevational view of a pencil equipped with a sharpener constructed in accordance with the present invention;

Figure 2 is a side elevational view of the sharpener detached from the pencil, showing the pencil sharpening blade, threaded portion and thread cutting member;

Figure 3 is a fragmentary side elevational view of the pencil with the sharpener detached and showing the threads thereon cut by the sharpener;

Figure 4 is a longitudinal sectional view of the sharpener;

Figure 5 is a cross-sectional view taken on line 5—5 of Figure 4; and

Figure 6 is a cross-sectional view taken on line 6—6 of Figure 1, showing the thread cutting element for the pencil carried by the sharpener, with a thread partially cut into the pencil.

Referring more in detail to the accompanying drawing, the pencil sharpener 10 is adapted to be attached to one end of the pencil 11 and may be permanently carried thereby or detached therefrom at will. The pencil sharpener 10 comprises a conical portion 12 provided with a longitudinally extending slotted opening 13 with a cutting

blade 14 secured as at 15 to one edge of the opening 13 and with the cutting edge of the blade 14 curved and directed inwardly of the conical portion 12 of the sharpener as clearly shown in Figure 5. The larger end of the conical portion 12 continues in a cylindrical threaded portion 16 and a terminal end plain portion 17. A triangular thread cutting finger 18 is struck-out from the cylindrical portion 17 of the sharpener and has the pointed end thereof directed or bent inwardly of the sharpener as shown in Figure 6.

In the use of the sharpener, the same is placed upon one end of the pencil 11 and the sharpener or pencil relatively rotated, the finger 18 being 15 in advance on the pencil with respect to the threaded portion 16 of the sharpener for cutting the threads 19 on the pencil 11 as shown in Figure 3. The threaded portion 16 of the sharpener moves into threaded engagement with the 20 threaded portion 19 on the pencil and the parts are thereby interlocking connected and during relative rotation, the blade 14 cuts a tapered end 20 on the pencil 11 and correspondingly shapes the pencil lead 21 that projects through the 25 smaller end of the conical portion 12 of the sharpener 10. The pencil may be rotated in the direction indicated by the arrow 22 in Figure 6 with the finger 18 cutting the threads 19 in the pencil 11 shown. The finger 18 cuts the threads 30 19 in advance of the threaded portion 16 of the sharpener to facilitate threaded engagement between the sharpener and pencil. The finger 18 is of a resilient character so that pressure thereon determines the depth of cut of the 35 threads 19 on the pencil 11 and the pointed end of the finger 18 when pressure thereon is relieved will be spaced from the bottom of the thread groove 19 so that reverse rotation of the sharpener is unhindered when it is desired to remove 40 the sharpener from the pencil.

From the above detailed description of the invention, it is believed that the construction and operation thereof will at once be apparent and while there is herein shown and described the 45 preferred embodiment of the invention, it is nevertheless to be understood that minor changes may be made therein without departing from the spirit and scope of the invention as claimed.

I claim:—

In a pencil sharpener, a conical body portion, a cylindrical threaded portion at the larger end of the conical portion, and a plain cylindrical terminal end outwardly of the threaded portion and of the same diameter as the threaded por- 55

tion, a sharpening blade extending longitudinally of the conical portion and a thread cutting finger carried by the terminal end of the sharpener outwardly of the threaded portion to provide a 5 thread on the pencil in advance of the threaded portion of the sharpener to receive the threads

of the latter, said thread cutting finger being resilient and exposed at the outer side of the plain cylindrical portion for manual pressure, whereby pressure thereon regulates the depth of the thread cut in a pencil.

ELIAS ERNEST GROSSMAN. 5
